(No Model.)

I. H. FARNHAM.
SIGNALING APPARATUS.

No. 444,108.

Patented Jan. 6, 1891.

UNITED STATES PATENT OFFICE.

ISAIAH H. FARNHAM, OF WELLESLEY, ASSIGNOR TO THE NEW ENGLAND TELEPHONE AND TELEGRAPH COMPANY, OF BOSTON, MASSACHUSETTS.

SIGNALING APPARATUS.

SPECIFICATION forming part of Letters Patent No. 444,108, dated January 6, 1891.

Application filed August 20, 1890. Serial No. 362,470. (No model.)

To all whom it may concern:

Be it known that I, ISAIAH H. FARNHAM, residing at Wellesley, in the county of Norfolk and State of Massachusetts, have invented 5 certain Improvements in Signaling Apparatus, of which the following is a specification.

This invention concerns telephone-circuits, and is an improvement in that class of such circuits wherein a number of stations are connected with the same main line. It is especially applicable to metallic circuits, but can also be applied to single-wire or earth-completed lines involving the same principles.

The most approved modern practice of telephone-circuit construction and arrangement where a number of stations are to be connected with the same circuit is to construct a metallic circuit between the two terminal stations, causing both wires thereof to loop 10 into all of the intermediate stations. The electric call-bell at each station is placed in a closed bridge or branch extending from one of the main wires of the metallic circuit to the other. The call-sending generator can 15 not be efficiently included serially in circuit with the said bell, because if it were the resistance of the said bell would form virtually a portion of the internal resistance of the generator, and make the latter so high that the 20 system would not be self-regulating. Therefore the call-generator is included in a second but normally-discontinuous bridge-circuit between the two wires of the main circuit, which bridge is closed only by and in 25 the act of sending a call-signal, and this closure may be effected either manually, as a distinct action, or automatically, in a manner well understood and extensively employed in the operation of such generators. The telephone at each station also is included in a 30 normally-discontinuous bridge between the main wires, which is held open by the presence of the receiving-telephone on its support, but which is closed when the said receiver is removed for use, so that the generator and telephone-bridge circuits are both 35 shunted by the bell-bridge. This arrangement has, for reasons unnecessary here to state, been found extremely satisfactory in 40 the operation of circuits connecting a num-

ber of stations. If, however, it be desired to apply the same principles in connection with a single-wire or earth-completed circuit, the several closed and discontinuous bridges, or derived or branch circuits, including, respectively, the call-bell magnets, the generating-armature, and the telephone or telephones, will necessarily be connected at each station in parallelism with the single line-wire, and will extend therefrom to earth. In the above 55 arrangement it is intended when the call-sending generator at any station is operated that the bells at all of the other stations of the circuit, including the bell at its own station, shall ring, the current developed by 60 said generator being divided among the electro-magnets of the said bells. A distinctive signal is assigned for each station, and though all stations hear every ring that one only 65 whose signal is given will respond. All of 70 the bell electro-magnets used in connection with systems of the character indicated are of high resistance and self-induction, they being often wound up to a resistance of five hundred and sometimes to one thousand 75 ohms.

It is evident from what has been stated that in the above class of circuits when any station-operator actuates his generator to call another station the said generator will, during the said call, be connected in multiple arc or in parallel with the ringing part or call-bell magnets of said instrument. I have ascertained that with this arrangement the closed bridge of the call-bell magnet of the 80 station sending the call becomes a very considerable obstacle to the strong and clear ringing of the other call-bells connected with the same line at distant stations—that is, it being by far the nearest call-bell bridge to 85 the particular generator at this time in operation, will divert from the main line a larger proportion of current than will any other one station or bell. While this disadvantage is not serious on a short line, it becomes of considerable moment in long ones, and is likely to be very detrimental to their satisfactory operation. It might be supposed that the easiest way to overcome or avoid this disadvantage would be to so arrange the ringing ap- 90 95 100

pliances as to disconnect the call-bell at the ringing-station altogether from the circuit during the operation of sending a call. It is, however, not practicable to do this, for the reason that the subscriber must hear his own bell ring or he would not know or would not be satisfied that his generator was doing any work at all.

In view of the foregoing considerations the object of my present invention is to prevent a disproportionate amount of the calling-current from being short-circuited at the calling-station, and to arrange the appliances and circuits at each station in such a way that outgoing signals shall be enabled to manifest themselves at the station where they are produced without depreciating their effect upon the call-bells at other stations. In carrying out these objects I provide means for increasing the resistance of the closed bell-bridge or branch circuit at the home or ringing station at the moment of sending the call from thence. I also do this by the same act which is necessary in order to send the call, and thus impose no additional work, operation, or thought upon the station-operator.

A practical means of embodying this invention is to place a suitable resistance (which may conveniently be formed of a coil or coils of insulated wire) in such relation to the press-button or automatic circuit-closer or changer which brings the generator into action that by the act of operating the said button, key, or circuit-changer (whether actuated manually or automatically) the said resistance shall be automatically or without preconcerted action interposed in the circuit of the home-bell magnets, whereby the said bell-bridge when a call is being sent by the generator at the same station shall have its resistance so raised or conversely have its conductivity so impaired that, though much nearer to the said generator than are the bell-bridges at the other stations, it shall present no greater facility for the passage of the current than is presented by the bell-bridges at the other stations, respectively. In other words, the said bell-bridge, though physically in close proximity to the generator at its own station, is electrically and for all practical purposes in the same relation with it and with the main circuit as if it were remote therefrom. The interposed resistance may, it is evident, be regulated or adjustable but I prefer a fixed resistance on the ground of simplicity. I find it useful, however, in some cases to provide not simply a resistance-coil, but an electro-magnetic coil, and in that event it becomes an inductive resistance and involves the utilization of self-induction. I am thus enabled to use a much smaller amount of wire coils or number of convolutions than otherwise would be necessary, and consequently a less-measured resistance.

In the drawings which accompany this specification, Figure 1 is a diagram showing a portion of a multiple-station telephone-cir-

cuit, in which my invention is disclosed. Fig. 2 is an enlarged diagram of a smaller part of said circuit, showing two stations only, with the electrical appliances and circuit-connections fully drawn out at one of the said stations. Fig. 3 shows the embodiment of the invention in a concrete apparatus, the several station appliances being electrically combined in accordance with said invention; and Fig. 4 shows a modified detail of the call-transmitting appliances, illustrating automatic means for bringing the generator into action.

The principle of my invention is fully disclosed in the diagram Fig. 1. A metallic circuit C is there indicated as extending between a number of stations, these being designated, respectively, by the numerals 1 to 6. One of these may, if desired, be a central station, as 1, or all may be subscribers' stations, as would be the case if C were a private line. The electrical apparatus and its connections are alike at all subscribers' stations. At each is a call-receiving electro-magnetic bell B, having its electro-magnets connected in a bridge or cross-wire conductor, forming a permanent connection between the two main-line wires L and L² of the main circuit C. This bridge-connection is permanently closed at all stations, and the bells being respectively included therein are all connected with the main circuit, and all will respond to signals sent from any station. At each station there is likewise a call-sending magneto-generator G, also included in a bridge-conductor between the two main wires, which bridge, however, is normally discontinuous, and only closed while a call is actually being sent. A key or circuit-closer k is also provided, and it will be seen that by means of its back or resting contact the said key is in connection with the closed bell-bridge, but that when pressed it is disassociated therewith and caused to form a new connection with the generator-bridge, which thereupon is closed, and by turning the handle c the said generator can be actuated to send an outgoing-call signal. Supposing that these appliances only were provided, as has heretofore been the case, if the line be long and if that one of the stations signaling be far from the others, it is obvious that much of the current generated would be shunted through the bell at the signaling-station, and that the other station-bells, deprived of their proper share of current, would be liable to ring imperfectly. Let it furthermore be supposed that station 5 under these conditions is sending a signal. It is clear that bell B at said station, being much nearer to its own generator than are any of the bells at other stations, will rob the said others of their due proportion of current, and that the major part of said current developed, leaving the generator G, say, by wire 12, will reach the other pole thereof by way of point g, section 14 of main wire L, point 11, bell B, point 8, and key k. The home-bell only will ring loudly, the others faintly. To remedy

this fault I provide a suitable resistance R and connect it in the bell-bridge serially with the bell B between the point 11 on line-wire L and 10 on line-wire L^2 ; but it is desirable that 5 this resistance shall only be brought into action at the station from which call-signals are being sent, and that at all other stations it shall be temporarily functionless. Therefore from a point 7 on the bell-bridge wire between the bell-magnet B and the resistance R , I run a wire e to the back stop or contact a of the key k , the stem of the said key being connected at 8 with the line-wire L^2 . Thus 10 the normal bell-bridge extends from point 11 on line-wire L to point 8 on line-wire L^2 through the key and its back contact, the resistance R being short-circuited or shunted out. This condition is maintained at all stations where signals are being received, so 15 20 that the ringing-current coming into the several stations is not weakened by the presence of the extra resistance in circuit, but can exert its full force on the bell to give a good ringing effect; but in sending a signal the crank 25 or handle c of the magneto-generator is revolved and at the same time the key k is pressed. This, as already explained, closes the generator-bridge from the point g on line-wire L to the point 8 on line-wire L^2 , the key 30 k having now become a part of the latter bridge. It is to be observed, however, that the movement of the key has not broken the circuit of the bell-bridge, which is still closed or continuous, but that it has removed the 35 short circuit or shunt from the resistance R , which during the signal-sending operation is thus introduced into the bell-circuit, raising the resistance thereof and preventing the currents generated in G from being short-circuited therethrough. 40

In practice of course there are but two main-line station-terminals or points of attachment for the apparatus. This is made clear by Fig. 2, which also shows the telephone connections. The normal circuit through the station 3 is, as in all cases, by way of the permanently-closed bell-bridge, from point 11 on line L , by wire 15, bell B , point 7, wire e , back contact a , key k , point 10, 45 wire 16, automatic switch s , lower contact-spring v thereof, and wire 18, to point 8 on line-wire L^2 . This represents the station apparatus at rest, the bell included in the only closed conductor through the station, the generator and telephone bridges open, and the resistance short-circuited or shunted. The 50 key k being depressed, the bell-circuit by way of e is broken; but the point 10 is reached through the resistance R . The generator 55 bridge is also closed, and follows the following route: from point 11, by way of wire 12, magneto-generator G , wire 22, key-anvil f , key k , wire 23, to point 10, and thence on the same path as the bell-bridge to point 8 on line-wire 60 L^2 . Only during the operation of the generator, therefore, is the resistance R introduced to the bell-bridge circuit. 65

The telephones are brought into connection with the main circuit by removing the receiver t from the automatic-switch hook s . 70 The hook-bar, yielding then to the spring x , flies upward, breaks contact with spring v and makes a new one with spring u , and the telephone-bridge is traceable as follows: from point 11 on line-wire L , by wire 17, contact-spring u , switch s , wire 16, point 10, wire 19, transmitter T , wire 20, receiver t , and wire 21, to point 8 on wire L^2 , the bell-bridge shunting the telephones while the latter are being used. 75

At station 2, Fig. 2, the bell-magnets B and resistance R are indicated in dotted lines.

Fig. 3 shows that the several station appliances hereinbefore described are all, as usual, inclosed in a single box, which is indicated by broken lines. The several instrumentalities and their electrical connections are substantially identical with those described, as shown in Fig. 2, and are similarly distinguished by letters and figures of reference, and it would therefore be useless to describe them again. The figure, however, is useful as indicating a suitable mechanical arrangement. The two upper binding-screw terminals represent, respectively, the line connections 85 90 95 100 105 110 115 120 125 130 135 140 145 150 155 160 165 170 175 180 185 190 195 200 205 210 215 220 225 230 wound helices of wire are the most convenient. Frequently, however, as already explained, the electro-magnetic coils may with advantage be employed, and I regard their 5 employment as being distinctively a feature of my invention.

The resistance required for the attainment of the best results may of course vary with the length of the circuit, the resistance of the 10 bell-magnets, and the distance between any special station and the others; but a very good average resistance, if it be simply made of coiled wire, is the same as that of the associated bell-magnet. If an inductive 15 resistance be employed, a much lower resistance will be required.

Although I have throughout this specification referred to the call-receiving device as a call-bell, it is evident that any other similar 20 device—such, for example, as a sounder or buzzer—is to be considered as involving the spirit of my invention.

I claim as my invention—

1. In an electrical signaling system, an electric circuit, an electro-magnetic signal-bell or 25 equivalent electro-magnetic signaling device in a permanently-closed branch of the said circuit, a signal-sending magneto-generator in a normally-open branch of the said circuit, 30 and means for increasing the resistance of the said bell-branch circuit while the said generator is being operated to send outgoing signals.

2. The combination, substantially as hereinbefore described, with an electric circuit extending between two or more stations, an electro-magnetic call-receiving device located at each station in a permanently-closed bridge or branch of said circuit, and a call sending 35 generator at each station in a normally-open bridge or branch of the said circuit parallel to the said closed branch, of means for closing the said generator-circuit to send an outgoing signal and for simultaneously increasing 40 the resistance of the parallel bell branch at the same station.

3. The combination of a metallic main-line circuit extending between and connecting two or more stations, an electro-magnetic call- 50 bell at each station in a permanently-continuous bridge between the two wires of said circuit, a call-sending generator at each station in a normally-open bridge, said bridge being when closed parallel with the bell-bridge, a resistance, as described, in a shunt of the said bell-bridge, and means, as indicated, for breaking the said shunt and for introducing the said resistance into the bell-bridge circuit when the generator is being 55 operated, and for withdrawing the same therefrom and for reinstating the said shunt when the generator becomes quiescent.

4. The combination of a metallic main-line circuit extending between and connecting a 60 number of stations, an electro-magnetic call-bell at each station in a permanent bridge between the two wires of said circuit, a re-

sistance adapted to be included with said call-bell in said bridge, but normally shunted therefrom, a call-sending generator at each 70 station in a parallel bridge of said circuit normally open, but adapted to be closed in the act of sending signals, and a circuit-changing device controlling the generator-bridge and the resistance-shunt and adapted 75 to close the one and open the other, and vice versa, according to its position.

5. In an electric signaling system, an electric main circuit extending between two or more stations, a normally and permanently 80 closed bridge or derived circuit at each station connected with said main circuit and including an electro-magnetic call-receiving device, a normally-open bridge or derived circuit at each station, also connected with said 85 main circuit in multiple arc with the said bell branch and including a signal-sending generator, an inductive resistance, substantially as described, connected with the said permanently-closed bell branch, but normally 90 shunted therefrom, and a circuit-changer controlling the said resistance-shunt and normally maintaining the continuity thereof, but capable of assuming a second position, in which the generator branch is closed and the 95 said resistance included in the bell-circuit, for the purposes specified.

6. A station apparatus for a multiple-station metallic circuit combining two main-line terminals, one for each wire of the said metallic circuit, a permanently-continuous conductor uniting the said terminals and forming a bridge between them, an electro-magnetic call-bell, and a resistance included in said bridge, combined with a normally-discontinuous independent bridge also extending between said terminals parallel to the first, a call-sending magneto-generator in the circuit of the said normally-open bridge, a shunt-circuit normally closed round the bell-bridge resistance, and a circuit-changing key or switch normally forming, together with its back contact, a portion of said shunt-circuit and maintaining the continuity thereof, but adapted when operated to form, together with its front contact, a portion of the generator-bridge and to complete the same, whereby the act of sending the signal is caused to add resistance to the bell-bridge.

7. The combination, substantially as described herein, of an electric call-bell and a call-sending magneto-generator connected, respectively, in a permanently-closed and a normally-open bridge between the line-terminals of a telephone-station apparatus, with a suitable resistance and a circuit-changer controlling the same and adapted to connect the said resistance in the call-bell circuit during the operation of the said generator in sending outgoing signals, but to withdraw 120 the same therefrom when said operation is 125 intermittent, substantially as and for the purposes set forth.

8. The combination, in a telephone signal-

ing system, of a metallic main circuit, a number of telephone-stations interconnected thereby, a permanently-continuous bridge or cross-conductor at each station, including the 5 call-bell magnets, a resistance-coil at each station, also included in the said bell-bridge, but normally shunted or short-circuited, a normally-discontinuous independent bridge or cross-conductor at each station, a call-sending magneto-generator connected with the same and arranged to be included therein when the said cross-wire is closed, and a circuit-changer constructed to close the said 10 open cross-wire during the operation of said generator and to simultaneously and auto-

matically break the resistance-shunt, whereby the said extra resistance may remain shunted at all stations except that sending a call and shall at said call-sending station be introduced into the bell branch, substantially as 15 described.

In testimony whereof I have signed my name to this specification, in the presence of two subscribing witnesses, this 6th day of August, A. D. 1890.

ISAIAH H. FARNHAM.
